HARRY GRUMBACH, OF NEW YORK, N. Y., ASSIGNOR TO SIMON ASCHER AND COMPANY, INC., OF NEW YORK, N. Y., A CORPORATION OF NEW YORK

KNITTED HEADWEAR

Application filed May 30, 1930. Serial No. 457,640.

This invention pertains generally to knitted articles and particularly to knitted headwear.

The invention will be described in connection with a head-piece known popularly as a beret; however, it is understood that it may be applied in many other ways.

The invention comprises forming the beret of a single flat strip of knitted material in a manner to form a device which is not only highly serviceable, but also neat and ornamental in appearance. The strip of knitted material is formed in a plurality of transverse sections, the rows of stitches in each section being disposed in angular relationship with the rows of stitches in each adjacent section, such arrangement comprising what is commonly known as a zigzag stitch. This results in side selvages of zigzag contour. The selvages of adjacent sections along one side are then joined together, as well as the ends of the strip, thus forming a bag-like object, having a free edge of zigzag contour. The intermediate portion of this bag is then expanded without materially expanding the free edge. The free edge is then turned backwardly upon itself and pressed into place. A head-piece of the beret type is thus formed. It is, of course, obvious that other styles of head-pieces could be made without departing from the spirit of the invention.

Referring to the drawings in which like reference characters are appended to like parts throughout the various figures:

Figure 1 is a plan view of a strip of knitted material having zigzag sides.

Figure 2 is a plan view, illustrating the manner of connecting the adjacent sections of one side of the strip shown in Figure 1.

Figure 3 is a perspective view of a hoop which is used in forming the head-piece.

Figure 4 is an elevational view of the bag formed from the strip shown in Figures 1 and 2.

Figure 5 is an elevational view, illustrating the shape of the bag after the hoop has been inserted therein.

Figure 6 is an elevational view, illustrating the final step in forming a beret.

Figure 7 is a bottom plan view of a finished beret.

Referring to the drawings at 1 is shown a longitudinal strip of knitted material, comprising a plurality of transverse sections. Each section 2 is made up of a plurality of rows of stitches 3, which are brought out to make selvages 4. The rows of stitches in adjacent sections are disposed angularly with respect to each other as illustrated at 5. I find it very convenient to have the rows of stitches of alternate sections run in the same general direction which results in zigzag side edges, as illustrated at 6 and 7. Such arrangement may be made by employing a zigzag stitch. While each transverse section may be of any width and need not correspond to the other sections, I find it very convenient to make the sections of uniform width.

In making up the head-piece the adjacent selvages 4 of the transverse sections are joined together, as illustrated in Figure 2. The ends of 8 and 9 are also joined, thus forming a bag-shaped article, similar to that shown at 10 in Figure 4.

The bag shown in Figure 4 may be made up into a head-piece of any desired shape. I find it very convenient to form the bag 10 into a beret by inserting a hoop, such as that illustrated at 11 in Figure 3, into the bag 10 to expand the walls thereof at about the centre, as illustrated at 12 in Figure 5. After the hoop has been inserted it is very convenient to press the material around the hoop so that it will remain in position after the hoop is withdrawn. The free edge 7 is then folded back upon itself, preferably along a line well within the zigzagged edge, so that all of the angular portions will lie along the bottom face of the beret. The edge 7 may then be pressed in place by any suitable means.

Means for pressing the edge 7, when reversed, is illustrated diagrammatically in Figure 6 which shows a lower matrix 13 and an upper matrix 14. If the upper matrix 14 is of lesser diameter than the interior diameter of the hoop 11, the operation of pressing the material into place around the hoop and pressing the reversed edge 7 may be

performed in one operation. The result is a finished head-piece 15 made from a single piece of material and highly ornamental in character.

5 It is, of course, understood that the strip 1 may be of any color or combination of colors, or adjacent transverse sections or pairs of sections may alternate in color.

10 It is obvious that the invention is not confined to any particular type of stitch, but applies to knitted materials in general.

One means for making a zigzag stitch is shown and described on pages 39 and 40 of the book entitled "Flat Machine Knitting and Fabrics", by H. D. Buck, copyrighted 15 1921 and published by Bragdon, Lord & Nagle Company, 334 Fourth Avenue, New York City, New York.

Having described my invention it is obvious that many modifications will be made in the same within the scope of the claims without departing from the spirit thereof.

I claim:

1. A knitted head-piece comprising a plurality of sections, the selvages of adjacent sections disposed angularly with respect to each other, so as to define zigzag sides, the adjacent selvages on one side and the ends secured together, said head-piece formed with 25 an expanded circumferential intermediate portion and the unsecured side turned back upon itself to form a decorative effect at the opening of the head-piece.

2. A knitted head-piece comprising a plurality of sections of equal width, the selvages of adjacent sections disposed angularly with respect to each other, thus forming zigzag sides, the adjacent selvages at one side secured together, said head-piece formed with 30 an expanded circumferential intermediate portion and the unsecured side turned back upon itself to form a decorative edge about the opening in the head-piece.

3. A process of making a knitted head-piece comprising forming a strip of knitted material with a side of zigzag shape, securing together adjacent angular portions of said side, securing together the ends of the strip, inserting a hoop in the bag thus formed, turning back the other side of said strip upon itself, and pressing the material about said hoop and about said turned back side to form said head-piece.

4. A knitted head-piece comprising a strip 45 of knitted material having at least one side of zigzag shape, the adjacent angular portions of said side secured together, the ends of said strip secured together, said head-piece formed with an expanded circumferential intermediate portion, and the unsecured side of said strip turned back upon itself to form a decorative effect at the opening of said head-piece.

5. A knitted head-piece comprising a strip 50 of knitted material made by zigzag stitching

and having sides of zigzag shape, the adjacent angular portions of one side secured together, the ends of said strip secured together, said head-piece formed with an expanded circumferential intermediate portion, and the unsecured side of said strip turned back upon itself to form a decorative effect at the opening of said head-piece.

70 In testimony whereof, I have signed my name to this specification this 24th day of 75 May, 1930.

HARRY GRUMBACH.
